MACHINE FOR MAKING TUBS AND THE
LIKE

Axel M. Walstrom, Minneapolis, Minn., assignor
to The Creamery Package Mfg. Company,
Chicago, Ill., a corporation of Illinois

Application September 29, 1938, Serial No. 232,295

7 Claims. (Cl. 147—1)

The invention relates to machinery for the manufacture of tubs and like containers of wooden stave construction, and more particularly to a machine for automatically assembling a set of staves and a bottom in accurate standard form and driving the hoops thereon to uniform position.

In the coopering of butter tubs and similar containers, it is common practice to arrange manually a set of pre-jointed tapered staves required for a tub within a pair of heavy steel rings or truss hoops, thus forming a shell in the form of a tub. The assembly is placed in a press where the nails are forced firmly into place about the staves. The trussed shell of staves is then placed in a machine wherein pressure rollers are applied to the inside surfaces of the staves to force their adjoining edges flush with the steel rings, to effect a smooth exterior tub surface. The ring trussed shell is then placed in a special lathe where the staves are trimmed and crozed for the reception of a tub bottom. The truss ring at the bottom or smaller end of the shell next is removed, permitting the bottom end portions of the staves to separate and expand circumferentially while the wooden disc bottom is forced into position in the croze groove. Following next, a chime hoop is forced over the re-compressed bottom ends of the staves, securing the staves and bottom in tight assembly. This operation is frequently done in a special machine. Thereafter the other truss ring is removed and the assembly is placed in another special machine where two light metal hoops are driven into permanent place to complete the tub assembly. The tub is then sanded exteriorly to finish the surface.

The foregoing series of operations requires an assembly line of benches, a number of special machines and several workmen. They require the manual handling of the heavy ring-trussed assemblies, and skillful manipulation of the machines to secure uniform finished tubs.

The principal object of this invention is to provide an automatic machine which will receive a loose set of trimmed and crozed staves, together with a bottom and the requisite hoops, and during its cycle of operation will completely assemble staves, bottom and hoops into a tight smooth finished tub.

Another object is to provide automatic means for controlling the successive operations of the machine to compress the staves, roll them into position forming a smooth outer contour, and to drive the hoops to a uniform standard position on the tub.

Other objects and advantages will be apparent

in the following detailed description of a preferred embodiment of the invention which I have selected for illustration in the accompanying drawings. It will be understood, however, that various changes in form, construction and arrangement may be made by those skilled in the art without departing from the spirit and scope of the invention as expressed in the appended claims.

Referring to the drawings, Fig. 1 represents a front view of the machine in elevation. Fig. 2 is a sectional side view in elevation taken on the plane of the line 2—2 in Fig. 1. Fig. 3 is a sectional plan view taken on the planes of the line 3—3 in Fig. 2. Fig. 4 is a partial sectional plan view, and Fig. 5 a partial front view in elevation, of the parts of the machine employed in introducing a set of staves, the sectional division of Fig. 4 being taken on the plane of the line 4—4 in Fig. 5. Fig. 6 is a partial side view in elevation in which the stave compression members are shown in uppermost position. Fig. 7 is a partial rear view in elevation illustrating the operating control mechanism, and Fig. 8 is a detailed view of the latter in changed position. Fig. 9 is a detailed view of another part of the control mechanism. Figs. 10 and 11 illustrate the bottom hoop carrier. Fig. 12 is a detailed sectional plan view of the mounting of the piston elevating crank shafts.

Generally stated, the operative arrangement of the machine as herein illustrated comprises a hinged table upon which may be laid out a serially arranged set of tub staves. Upon swinging the table to vertical position, the staves may be pushed laterally from the table into a pair of circular upper and lower stave end guides wherein a tub bottom is supported, thus forming a loose assembly of staves and bottom in tub form. Lowering the table to horizontal position operates to swing the upper stave guide free of the assembly, whereupon the operator manually places the requisite hoops loosely upon the stave assembly. The machine is then put in operation, causing a group of segmental stave-compressing and hoop-driving members to be lowered about the stave assembly. These members engage the hoops and draw them into position, and at the same time radially compress the assembly of staves into tight lateral contact. Meanwhile a stave rolling device, positioned inside of the tub assembly, operates to press the stave edges into smooth contour against the compression members. The compression members being locked in lowermost position by an overhead toggle device,

a piston, which supports the lower ends of the staves, is actuated with an upward thrust to finally drive the compressed staves tightly into the hoops held by the compression members. 5 Thereafter, the compression members are released and withdrawn from the finished tub, which may then be removed manually, the machine being then ready for repetition of the cycle.

More specifically described with reference to 10 the drawings, the numeral 21 indicates a curved table having width and length adapted to accommodate a set of trimmed and crozed staves 22 laid out on its surface in edge to edge relation and in requisite number for one tub. The staves are 15 retained upon the table by side flanges 23 and 24, and by overlying bars 25 and 26 secured by suitable brackets fastened to the flanges 23 and 24.

The table is supported for swinging movement 20 by hinges 27 secured to the underside of the table and to a bar 28, the latter being pivotally supported upon a pair of arms 29 and 30 secured respectively upon the shafts 31 and 32 having suitable bearings 33 and 34 mounted on the frame 25 cross members 35 and 36 secured in the spaced machine frame standards 37, 38 and 39. In horizontal position, the table 21 rests upon a pair of stops 40 mounted on the frame standard 37.

The table 21 is normally in horizontal position 30 as shown in Figs. 1 and 3. To begin operation of the machine, a set of staves 22 is laid out on the table, the latter is swung on the hinges 27 into vertical position and moved endwardly on the pivoted arms 29 and 30 to the position shown 35 in Figs. 4 and 5. In this position of the table, the staves 22 are manually moved from the table into a stave supporting guide ring 41 of which the flanged bottom is secured to the frame standards 38 and 39. The guide ring is provided with 40 an entry slot 42 through which the lower ends of the staves pass as they are pushed from the adjacent end of the lifted table. With the entire set pushed into the guide ring 41, the staves form a loose tub assembly.

45 During the movement of the staves from the table into the guide ring 41, the upper ends of the staves are guided by a flanged guide plate 43, having a slot 44 in its downturned flange for entry of the staves. The guide plate 43 is supported for movement into operative position coincidentally with the swinging of the table 21 into vertical position for discharging a set of staves. A pair of arms 45 support the guide plate by pivotal connection with a pair of lugs formed on 50 opposite sides of the plate, the arms being secured upon a rock shaft 46 having bearing support on a pair of studs 47 fixed upon a pair of upright frame standards 48. A lever 49 is secured on the end of the rock shaft 46, the free 55 end of the lever having pivotal connection with a link 50, the latter having pivotal connection with a lever 51 secured to the shaft 32.

By means of the levers and link last described, the endward movement of the table 21 toward the 60 guide ring 41 effects the swinging of the guide plate 43 into position over the guide ring 41 to receive the upper ends of the staves when pushed from the table into the guide ring, as shown in Fig. 5. The reverse movement of the table effects the swinging of the guide plate away from the upper ends of the staves assembled in the 65 guide ring and into the position shown in Fig. 2, where it remains during the operating cycle of the machine.

70 Before swinging the guide plate 43 into posi-

tion to receive the staves, a tub bottom 52 (Fig. 2) is manually placed upon the upper end of a stave alining device positioned inwardly of the staves when assembled in the guide ring, and fully described hereinafter. The guide plate 43, 5 carries a rotatable disc 53 mounted concentrically with the plate 43 and supported on a pivot bolt 56. When guide plate 43 is swung into position to receive the staves, the disc 53 bears upon the tub bottom 52 and secures it in position for 10 the entering staves to pass around it with their croze grooves in register with the periphery of the tub bottom.

Within the guide ring 41 is a piston 55 having a peripheral flange 56 upon which rest the lower 15 ends of the staves 22, the piston 55 being vertically movable through a short stroke. The piston 55 is operatively supported on two pairs of connecting rods 57 having wrist pin connections 58 in brackets formed on the lower side of the piston 55, and actuated by a pair of crank shafts 59 journaled in the lower end of a crank case 60 supported on cross frame rods 35 and 36 secured in the frame members 37, 38 and 39. The connecting rods 57 are mounted on the crank pin 25 portions 61 (Fig. 12) of the two crank shafts. The two crank shafts are operated in opposite synchronous rotation by two pairs of inter-meshing spur gears 62, one of the crank shafts being 30 driven by a pair of gears 63 driven by a pair of pinions 64 fixed on shaft 65 carrying a pair of gears 66 in driven mesh with a pair of pinions 67 fixed on the main drive shaft 68 journaled on the frame members 37, 38 and 39, and carrying a drive pulley 69.

Extending vertically through the center of the piston 55 is a rotatable shaft 70 journaled in the piston and in the bottom portion of the crank case 60. Vertical shaft 70 is driven by a spline mounted bevel gear 71 in driven mesh with a 40 bevel pinion 72 fixed on a shaft 73 journaled in the side of the crank case and extending into a worm drive unit 74 wherein the shaft 73 is in conventional gear and worm driven connection with the main drive shaft 68. The shaft 70 45 carries a central free hub 75 having upper and lower radial flanges 76, each provided with four radial slots 77 in which are supported, for free radial movement and rotation, four vertical shafts 78 each carrying four resilient rollers 79 adapted to contact the inside surfaces of the tub staves and press them into surface alinement against the outside hoop driving rings later described. A pair of cam plates 80 are fixed on the upright shaft 70, one above and one below the hub 75. 50 The cams 80 engage the roller shafts 78 at their upper and lower ends, forcing the rollers into pressure contact with the staves and rotating the entire roller supporting assembly.

After a set of staves has been pushed into the 55 guide ring 41 and guide plate 43, and loosely assembled around the tub bottom, guided inside by the radial flanges 76, the operator moves the table 21 back and lowers it to horizontal position, thereby swinging the guide plate 43 up and away 60 from the staves. The operator then manually places two wire hoops 81 over the staves, and also places a chime hoop 82 on a guide fixture (Figs. 10 and 11) and places that on the upper 65 ends of the staves. The chime hoop guide fixture comprises a split ring 83, having a slightly tapered outer periphery adapted to support the chime hoop 82, the latter having spaced indentations in register with an annular groove 84 formed in the periphery of the ring for properly position- 70 75

ing the hoop on the ring. A split guide sleeve 85 is positioned within the ring 83, one edge portion of the sleeve extending outwardly of the ring. The sleeve is retained in position by spaced pins 86 mounted in the ring and extending through openings in the sleeve. With the fixture in place upon the assembly of staves, the sleeve 85 extends inwardly of the stave ends and the ring 83 rests upon the stave ends, thus positioning the chime 10 hoop for passage from the ring 83 to the end portions of the staves as the latter are compressed about the tub bottom, as hereinafter described. The ring 83 and sleeve 85 are sufficiently resili- 15 ent to permit forcing the hoop 82 into position on the staves without distortion in passing from the tapered ring.

The operator, having started operation of the machine as later described, a stave compressing and hoop setting device is lowered over the assembly of staves. This device comprises a longitudinally segmental conical assembly of members 87 adapted to slide down over the outer surface of the stave assembly, and having annular notches 88 formed in their inner surfaces to engage the wire hoops 81 and move them downwardly on the staves until the lower ends of the members 87 engage the upper edge of the guide ring 41. The members 87 are supported in normal lateral contact and alinement by a coiled spring 89 lying in an annular groove formed in the outer surfaces of the members 87. The latter are further supported within a pair of outwardly contacting, spaced compression rings 90 having lateral guiding support on four upright frame standards 91. The upper compression ring 90 normally lifts the members 87 and supports them in disengaged position by means of the radial flanges 92 formed on the upper ends of the members 87 and resting upon the ring. 25 As the members 87 engage the tub staves in descending, the rings 90 pass down the conical assembly of the members and compress them inwardly upon the staves, forcing the latter into lateral engagement with each other, and establishing the outer contour of the finished tub.

Embracing the upper or inverted bottom ends of the staves assembled about the tub bottom, is another portion of the stave compressing and hoop-setting device comprising an assembly of 30 L-shaped segmental members 93, the lower arcuate legs of which pass down around the ends of the staves. The members 93 have inner notches 94 forming an annular shoulder which engages the chime hoop 82 and forces it off the hoop supporting ring 83 and onto the compressed stave ends. The members 93 are laterally supported within a third compression ring 95, functioning similarly to the rings 90 and also laterally guided by the standards 91. The members 35 93 are suspended from an annular cross head 96 having oversize openings in its inner portion through which bolts 97 loosely pass and are secured in the upper legs of the member 93. The cross head 96 is also laterally supported and 40 guided by the standards 91. Further support for the cross head 96 and the suspended members 93, adapted to maintain proper spaced relation between the members 93 and the lower compression members 87, is provided by an annular group of vertical spacer bars 98 secured in the outer flange portion of the cross head, extending freely through the compression ring 95 and endwardly abutting the flanges 92 on the upper ends of the members 87.

The two compression rings 90 and ring 95 are

adjustably inter-spaced and connected by four screw threaded rods 99 secured in the flange of the lower ring 90 and extending through the upper ring flanges, being secured thereto by nuts 100. The upper ends of the rods 99 are fastened 5 to a pair of cross bars 101 positioned above the cross head 96, and at the center of each of which is secured a chain 102, the pair of chains being operated to raise and lower the entire assembly of compression members and rings. The chains 10 102 pass over a pair of driving sprockets 103 fixed on a drive shaft 104 journaled in side frame members 105, the latter being supported on the upright standards 91, 43 and another rear pair of upright standards 106. A pair of rollers 107 are 15 mounted on stub shafts 108 secured in the frame members 105, and are positioned in front of the sprockets 103 to prevent the chains from jumping off the sprockets. From the driving sprockets 103 the chains pass over a pair of idler sprockets 20 109 loosely mounted on a shaft 110 fixed in the frame members 105, thence downward and attached to a counterweight 111 vertically slidable on the guide standards 48.

The shaft 104 is driven by a conventional worm gear drive unit 112 of which the worm shaft 113 extends through a splined sleeve 114 and a loose pulley 115 driven by a belt 116 driven in turn by a reversible electric motor 117. The pulley 115 carries a conventional friction clutch 118 controlled by and driving the sliding splined sleeve 114. The sleeve 114 is oppositely connected with a similar friction clutch 119 carried by a pulley 120 loosely mounted on the shaft 113 and secured against rotation by attachment to a frame cross bar 121, whereby engagement of the clutch 118 functions as a brake on the shaft 113.

Automatic operation of the chain drive actuating motor 117, to lower the stave compressing and hoop-setting mechanism and to elevate it again, is initiated by a foot pedal 122, laterally supported by a pivoted link 123 and pivotally attached at its upper end to a lever 124 fixed on a rock shaft 125 extending rearwardly. The rock shaft 125 is journaled in suitable bearing 45 brackets mounted on cross frame members 126 and 127, and rearwardly carries another fixed lever 128 pivotally connected to a link bar 129 which is oppositely connected to a cam lever 130 fixed on another rock shaft 131 journaled in a 50 suitable bearing bracket mounted on a cross frame member 132, and in the guide ring 41. The upper portion of the cam lever 130 is formed with two lateral cam lobes 133 and 134 describing an intermediate recess. The cam portion of the 55 lever 130 is in operative contact with the swinging handle 135 of a conventional reversing switch 136 controlling the electric power circuits to the motor 117.

The handle 135 is provided with a roller 137 60 which is positioned within the recess between the two cam lobes when the switch is in neutral or "off" position. Stepping on the pedal 122 operates the cam lobe 134 to throw the switch handle 135 to that side which starts the motor 117 in 65 direction to lower the stave compressing and hoop-setting mechanism upon the staves, and consequently to raise the counterweight 111. The rock shaft 131 carries also a fixed vertical lever 138 having pivotal connection with a link 70 bar 139 extending upwardly, and connected to a pivot bracket 140 which is pivoted to a pair of bell cranks 141 loosely mounted on the shaft 110 and forming a shifting yoke for conventional operation of the splined sleeve 114. Operation 75

of the foot pedal to close the switch 136 simultaneously operates the shifting cranks 141 and sleeve 114 to engage the chain driving clutch 118, while opening the switch (positioned as shown in Fig. 7) disengages the clutch 118 and engages the brake clutch 119.

Having started the mechanism to lower the stave compressing and hoop-setting device, the counterweight 111 rises until it engages a stop 142 fixed on a vertical bar 143 extending downward and pivotally connected to a laterally extending lever 144 fixed on the rock shaft 131, preferably integral with lever 138. Engagement with the stop 142 raises bar 143 and lever 144, 10 rotating shaft 131 and cam lever 138 to return switch handle 135 to open switch position, and releases clutch 118 and engages brake 119, thus bringing the mechanism to a stop with the hoop-setting device in lowermost position about the staves, while the crank shafts 59 and the stave 15 rolling drive shaft 70 are automatically started in operation, as hereinafter described, to roll the staves into even relation and lift the piston 55 to drive the staves into tight engagement within 20 the hoops.

The stave compressing and hoop-setting mechanism is held in lowered position against the upward thrust of the piston 55 by a toggle device comprising a pair of lower toggle bars 145 pivotally connected to a short shaft 146 mounted in the cross head 96, and a pair of upper toggle bars 147 pivotally mounted on the chain drive shaft 104, the two pairs of toggle bars having pivotal connection with each other upon the cross bar 148 extending through the several toggle bars. The lower toggle bars 145 extend upwardly of the pivot bar 148 and each has at its upper end a rearwardly extending integral horn 149 forming a toggle lock by engagement with a pair of arms 150 fixed on the drive shaft 104 and carrying rollers 151 which ride over the arcuate upper surfaces of the horns 149 when the toggle is closed and come to rest in position shown in Fig. 2. The lower bars 145 also carry opposite locking lugs 152 which engage the forward edges of the upper bars when in closed position and prevent rearward opening of the toggles.

The compression rings 90 and 95 are forced down into close engagement with the segmental members 87 and 93 by means of a pair of upwardly extending bars 153 pivotally connected to the ring supporting cross bars 161, and having an attached guide strap 154 embracing the toggle lower bars 155. The cam faced upper ends 155 of the bars 153 are engaged, during the closing movement of the toggle members, by a pair of rollers 156 mounted on the lower rearwardly curved extended ends of the upper toggle bars 147, which force the bars 153 downward and thereby move the rings 90 and 95, through the cross bars 161 and ring spacer rods 99, downward into tight position.

The mechanism for automatically starting the drive for the piston lifting cranks 59 and the stave evening rollers 79, comprises a sleeve 157 (Figs. 3 and 9) freely mounted on the pedal shaft 125 and having a pair of fixed arms 158 forming a shifting yoke in operative engagement with a clutch sleeve 159 splined on the main drive shaft 68. Shifting of the sleeve 159 in one direction engages a conventional clutch 160 in the drive pulley 69, thus driving the gear train operating the piston cranks 59 and roller shaft 70. Shifting the sleeve reversely releases clutch 160 and engages a brake clutch 161 similarly mounted in

a pulley 162 loosely mounted on the shaft 68 but secured against rotation by attachment to the machine frame. Mounted on the sleeve 157 is a ratchet collar 163 having notches 164 and 165 (Fig. 9) engageable by dogs 166 and 167 pivoted upon a bracket 168 fixed on the shaft 125. The dogs are drawn toward the ratchet collar by a spring 169. The dogs are L-shaped with their outer edges forming an arc about the axis of the shaft 125 and positioned to be engaged by a pair of diametrically positioned lugs 170 and 171 on the side of the adjacent gear 63. A lever arm 172 (Fig. 3) is also fixed on the pedal shaft 125 for engagement by lug 170 on the gear 63.

When the operator first steps on the pedal 122 to start the lowering of the stave compressing and hoop-setting device, the dog bracket 168 is rotated downward so that the dog 166 drops into engagement with notch 164 in the ratchet collar 163. The lug 170 on gear 63 is cut away on one side so as to allow dog 166 to engage notch 164 while it holds dog 167 out of engagement with notch 165. When the hoop-setting device reaches lowermost position, and rock shaft 125 is rotated by the lever 128 back to normal or neutral position, dog 166 rotates collar 163 and sleeve 157 and shifts clutch sleeve 159 to engage clutch 160 and start operation of the gears for elevating piston 56 and rotating rolls 79, while the hoop-setting device remains stationary with the toggle support closed.

A one-half revolution of gear 63, which has effected the maximum elevation of piston 56, carries lug 170 into engagement with lever arm 172 which rotates rockshaft 125, thereby operating through lever 128, link 129 and cam lever 130 to throw the switch handle 135 into position (Fig. 8) to reversely close the power circuit to motor 117. This latter movement of the cam lever 130 also operates, through its supporting shaft 131, the lever 138 and the link bar 139, to disengage the brake clutch 119 and engage the main drive clutch 118, thereby driving the shaft 104 in reverse direction to unlock and open the toggle members 145 and 147 and to operate the chains 102 to elevate the stave compressing and hoop-setting mechanism. Some slack is provided in the chain connection to allow the toggle to break before lifting the hoop-setting mechanism. The chains first lift the rings 90 and 95, freeing the segmental members 87 and 93 to expand and release the tub, then by engagement of the upper ring 90 with the flanges 92 to lift the whole structure, the toggle members folding as shown in Fig. 6.

When the arm 172 rotates shaft 125 to start elevating the hoop-setting device, the dog bracket 168 is rotated upwardly, but without effect on the sleeve 157, as the lug 171 on gear 63 is then in position to contact the dog 166 and lift it out of engagement with notch 164, so that the dog passes over the notch as the bracket 168 is rotated. Lug 171 is cut away oppositely to lug 170, so that with the latter rotation of bracket 168, the dog 167 drops into engagement with notch 65 165 at the end of the movement.

All of the mechanisms are now operating to elevate the hoop-setting device and to lower piston 56. When the counter-weight 111 reaches lowermost position it engages another stop 173 70 fixed on the bar 143, which operates the lever 144 to shift the cam lever 130 again to neutral position and the switch handle 135 to open position and stop the motor 117, at the same time again opening drive clutch 118 and engaging brake 75

clutch 119. Likewise, through link 129 and lever 128, the shaft 125 is operated to lower the dog bracket 162, whereby the dog 167, now in engagement with notch 165, effects reverse rotation of 5 sleeve 157, which disengages drive clutch 160 and engages brake clutch 161. As all of the mechanisms come to rest, dog 167 is again engaged by the lug 158 which lifts it out of notch 165, so that the dogs are set for repetition of the operating 10 cycle.

The operator now removes the chime hoop retainer from the tub, and removes the finished tub from the guide ring 34, whereupon the machine is ready for the entry of a new set of staves 15 and repetition of the operation.

I claim as my invention:

1. A device for finally assembling a loosely assembled set of container staves and a bottom and for positioning side hoops and a chime hoop thereon comprising in combination, supporting means for said assembled staves and bottom, an annular group of spaced segmental members movable into outward contact with said assembled staves, said members having notches in 20 their stave contacting surfaces adapted to engage side hoops loosely positioned on said staves and to move said hoops into tight engagement with said staves, a guide fixture positioned endwardly of said staves adjacent said bottom and 25 adapted to support a chime hoop, a second annular group of spaced segmental members movable into outward contact with the end portions of said staves adjacent said bottom, said latter members having notches adapted to engage a 30 chime hoop supported on said guide fixture and move said chime hoop from said fixture to and upon the adjacent end portions of said staves, a pair of compression rings mounted on said first group of members, another compression ring 35 mounted on said second group of members, said rings being movable longitudinally of said members respectively to compress said members and thereby compressing said staves to receive said hoops and secure said bottom, means for moving 40 both groups of said members into and out of contact with said staves, and means for moving 45 said compression rings longitudinally of said members respectively.

2. A device for finally assembling a loosely assembled set of container staves and a bottom and for positioning side hoops and a chime hoop thereon comprising in combination, supporting means for said staves and bottom, an annular group of spaced segmental members movable into outward contact with said staves, a second 50 annular group of spaced segmental members movable into outward contact with the end portions of said staves, each of said groups of members having hoop-engaging notches formed in 55 their stave contacting surfaces, a pair of compression rings mounted on said first group of members, another compression ring mounted on said second group of members, said rings being movable longitudinally of said members respectively to compress said members and thereby 60 compress said staves, an end flange formed on each of said first group of members, said end flanges having supporting engagement with one of said pair of rings when in retracted position, 65 a cross head loosely attached to said second group of members, a plurality of spacer bars secured in said cross head and normally abutting the ends of said first group of members, a plurality of connecting rods secured to said compression rings, a cross bar attached to said con-

necting rods, means for moving said cross bar and thereby said rings and both groups of said members to and from said staves, a toggle mechanism connected to said cross head and operable through said cross head and spacer bars to move both groups of said members into predetermined longitudinal positions upon said staves and to lock said members in said positions, and means connected to said cross bar and operable through said cross bar and said connecting rods 10 to move said compression rings into predetermined positions upon said members.

3. A device for finish assembling a loosely assembled set of container staves, bottom and hoops comprising in combination, supporting means for said staves, means for compressing said staves and for positioning said hoops thereupon, means for locking said stave-compressing and hoop-positioning means in pressure engagement with said staves, a rotatable support positioned within said assembled staves in co-axial relation thereto, a roller shaft loosely mounted on said support, a roller operatively mounted on said shaft adjacent the inner surfaces of said staves, a rotatable cam having engagement with 20 said shaft and operable through said shaft to rotate said support and to move said roller into pressure contact with said staves, and means for rotating said cam.

4. A device for finish assembling a loosely assembled set of container staves, bottom and hoops comprising in combination, supporting means for said staves, means for compressing said staves and for positioning said hoops thereupon, means for locking said stave-compressing and hoop-positioning means in pressure engagement with said staves, rotatable means positioned for operative contact with the inner surfaces of said staves and operable to move adjacent staves into surface alignment, a reciprocating member positioned adjacent the ends of said staves, said member being operable to engage and force said staves while under compression into final position within said hoops, and means for reciprocating said member.

5. A device for finish assembling a loosely assembled set of container staves, bottom and hoops comprising in combination, supporting means for said staves, means for compressing said staves and for positioning said hoops thereupon, means for locking said stave-compressing and hoop-positioning means in pressure engagement with said staves, a rotatable shaft positioned coincident with the axis of said stave assembly, a hub freely mounted on said shaft and having a plurality of radially slotted flanges, a plurality of shafts supported respectively in said radial slots, rollers mounted on each of said shafts, said rollers being adapted to contact the inner surfaces of said staves, and a pair of cam plates secured to said rotatable shaft, said cam plates having operative contact with the respective roller shafts effective upon rotation of said rotatable shaft to move said rollers into pressure contact with said staves and to revolve said rollers and roller shafts about the axis of said rotatable shaft.

6. A device for finish assembling a loosely assembled set of container staves, bottom and hoops comprising in combination, means for laterally supporting said staves, means for compressing said staves and for positioning said hoops thereupon, means for locking said stave-compressing and hoop-positioning means in pressure engagement with said staves, means

positioned within said assembled staves for rolling said staves into uniform surface contour, a reciprocatory piston mounted within said stave supporting means and abutting the ends of said staves, crank means having operative connection with said piston, and means for operating said crank means during the period of compression of said staves whereby said piston is moved to force said staves endwardly into final position within 10 said hoops.

7. A device for finish assembling a loosely assembled set of container staves, bottom and hoops comprising in combination, supporting means for said staves and bottom, means movable into outward engagement with said staves for compressing said staves and for positioning said hoops thereupon, means operable to lock said stave compressing and hoop-positioning means in pressure engagement with said staves, 15 rotatable means for rolling said staves into uniform surface contour, reciprocatory means for forcing said staves into final position within said hoops, intermittent reversible actuating means for said stave-compressing and hoop-positioning 20 means and for said locking means, a control clutch for said actuating means, intermittent driving means for said stave rolling means and 25

for said final stave-positioning means, a control clutch for said driving means, a reversible prime mover for said actuating means having a power cut-off and reversing switch, a continuously operable prime mover for said driving means, an 5 automatic trip means controlling said clutch for said actuating means and partially controlling said switch, and a second automatic trip means controlling said clutch for said driving means and partially controlling said switch, the operation 10 of said pair of controlling trip means being initiated by hand to cause said actuating means to move said stave-compressing and hoop-positioning means into pressure engagement with said staves and to lock the same in said position, 15 and said pair of controlling trip means being automatically operable thereafter in sequence to stop operation of said actuating means to start operation of said driving means for driving said stave rolling means and said reciprocatory stave 20 forcing means, to stop operation of said driving means, to start reverse operation of said actuating means for unlocking said locking means and for withdrawing said stave-compressing and hoop-positioning means from said staves and to 25 stop operation of said actuating means.

AXEL M. WALSTROM.
